UNITED STATES PATENT OFFICE.

ROBERT V. BINGAY, OF PITTSBURGH, PENNSYLVANIA, ASSIGNOR TO PITTSBURGH
TRANSFORMER COMPANY, A CORPORATION OF PENNSYLVANIA.

TRANSFORMER.

1,421,899.

Specification of Letters Patent. Patented July 4, 1922.

Application filed October 17, 1919. Serial No. 331,325.

To all whom it may concern:

Be it known that I, ROBERT V. BINGAY, a citizen of the United States, residing at Pittsburgh, in the county of Allegheny and State of Pennsylvania, have invented certain new and useful Improvements in Transformers, of which the following is a specification.

This invention relates to transformers, and the chief object of the invention is to form the transformer coils in such manner that they will be rigid and securely protected against relative shifting and short circuiting in use and at the same time permit the core and coil parts to be arranged, shaped and proportioned for most efficient distribution of the current and magnetic flux and thereby secure improved operating characteristics.

Other objects and advantages of the invention particularly in connection with oil cooled transformers having a double magnetic circuit will appear from the following description.

In the accompanying drawings the invention is shown as applied to a double magnetic circuit type of transformer which includes the so called "shell-type" transformer, but it will be understood that it may be applied to any type.

Fig. 1 is a diagrammatic illustration of the method of building up the coils;

Fig. 2 is a horizontal sectional view of a transformer illustrating one embodiment of the invention;

Fig. 3 is a plan view of the coil shown in Fig. 2, and

Figs. 4 and 5 are respectively vertical front and side views of the same with the tank sides and upper portions omitted.

In prior transformers difficulty has been experienced in making them sufficiently thick from front to back for maximum efficiency of the material employed and at the same time providing coils of desired strength to resist relative shifting and the wearing down and breakdown of the insulation. Each change in a transformer current brings a change in the magnetism, and resultant stresses between turns of the primary and secondary coils and there are also stresses between primary and secondary coils often tending to violently drive them apart. These stresses are applied to every part of the coiled wire so that any lengths of wire that are not securely held, shift relatively to the others and the loosening once started increases with every subsequent shock until finally the insulation breaks down and a short circuit occurs. Where the coil section is not of continuous curvature as in oblong coils with bends at the ends, the straight side strands cannot be laid and held snugly against adjacent inner coils because the winding tension on these straight strands is parallel to them and cannot press them together and when the bend at the next succeeding end is made the bending of the wire there tends to raise and loosen the straight side strand just previously laid. These oblong coils, therefore, are necessarily weak in their straight strands and the longer the oblong the greater will be the tendency of the side strands to loosen, so that the practicable length of transformer coils and the corresponding thickness of the core have hitherto been severely limited.

Conditions of efficiency and economy, on the other hand, require a narrow thick core construction with a correspondingly narrow and long coil. Economy of copper demands a small coil and in turn a small cross section of core through the coil with great density of magnetic flux there and correspondingly greater magnetic resistance at this portion of the core, and in order to compensate for this a lowered resistance and enlarged cross section are necessary for the remainder of the core. If the core is of generally square section as with a circular form of coil desirable for strength these enlarged portions of the core outside of the coil assume great widths extending far from the coil so that the tendency of the magnetic circuits to expand centrifugally is given full play and the inner portions of the surrounding part of the core carry little flux and the outer portions are dense with it. This uneven distribution of flux in turn prevents the desired decrease in magnetic resistance and a large portion of the core is practically wasted while the core itself and the supporting parts are extremely bulky. It is therefore highly desirable to reduce this excessive width of core, minimize the over-all dimensions and material required, prevent the spreading of the magnetic flux and produce a more even and efficient magnetic flux distribution; and the only way this can be done is to increase the core depth so as to give a construction deep from front to back and oblong in sec-

tion. Thus, while considerations of mechanical coil strength and durability favor a round coil and a core square in section, considerations of efficiency favor a core having one dimension greater than the other in section; and commercial practice has not heretofore attained the best efficiency and the desired strength and durability.

The coil and core provided by the present invention avoids the disadvantages of the prior constructions in that it permits a thick and narrow section of core to be used and at the same time the coil is itself rigid, strong and self supporting in all its parts. With it the core may be made of any desired sectional construction for best economy of material and efficiency in performance and the construction will also be strong and with all parts permanently secured against loosening or distortion.

In the drawings, Fig. 1, the coil 5 is shown in process of formation the wound portion 6 being fast on rotatable mandrel 7 while the winding length 8 is gripped by tension device 9. The shape of the coil and mandrel is elliptical or oval in section so that the winding of each layer takes place on a surface of continuous though variable curvature and having comparatively large radii of curvature throughout. Hence though the coil is long and narrow in section it is wound easily and tightly and under continuous and uniform tension, like a circular coil, from end to end of the wire. Each increment of the wire is flexed and pressed tightly against the next adjacent inner portion of the coil and the whole of the wire remains shaped and tensioned into a coil every portion of which is arched and securely self supporting with no weak parts to become loosened in service. Thus the successive layers of the coil in the same or adjacent planes tend to support each other, and the successive longitudinal layers of the coil build up what is in effect an elliptical sleeve surrounding the core leg and providing vertical channels for ventilation or oil cooling.

As illustrated in the drawing the coil structure of this invention even for very large transformers may safely be made unitary without the assembly of separately wound and separately reinforced sections. The mutual supporting action of all the parts throughout the entire unitary coil structure of this invention makes sectional reinforcement unnecessary and avoids loosening at any point. In the transformer construction shown there is an innermost barrier 10 coextensive with middle leg 21 in the core, around this is wound one coil 11 of the low tension winding made up of successive vertical layers to form an elliptical sleeve, then a barrier 12 of insulating material then a high tension coil 13, another barrier 14 and the other coil 15 of the low tension wind-

ing, coils 13 and 15 being made up of successive vertical layers as in the case of coil 11. Additional barriers of insulation 16 fill the spaces between the coils and the core. In order to ventilate or cool the coils adjacent windings are separated by vertical strips 17 of insulating material so as to provide vertical ducts 18 between one or more of the coil layers lying in the same plane for the cooling fluid which gains access to these ducts at the bottom and also through the intermediate open spaces 18' provided in winding the coils; the ducts also insulate the layers of the coils in the same plane from each other resulting in economy of material and greater efficiency, as the ducts serve two purposes. Thus with the unitary coil construction of this invention vertical ducts continuous from bottom to top of the coils are provided for the cooling fluid, saving in the amount of metal and avoiding weakening and breakdown of the insulation. The core 19 is also provided with cooling ducts as 19' if desired. In some cases the ducts may be eliminated altogether due to the greatly increased radiating surface.

The oval or elliptical contour of the outer periphery of the coil also permits outside legs such as 22 and 23 to be closely positioned cutting down the over all width of the transformer, because the tapering corner spaces 24 provided between the coil and these core legs give extended access of the cooling fluid to the surfaces of the parts while at the center the core and the coil insulator may be in contact.

As shown in Figs. 2 to 4 the core 19 is preferably of the double magnetic circuit type, that is, one having an interior core surrounded by the coil and at least two outer legs connected with the interior core and in which the interior core may form a common path for the flux or may provide independent paths therefor. In such a core the center leg 21 within the coil is only about one sixth of the flux path in length, the remaining five sixths formed by the yokes and legs 22, 23 being free to have the most efficient size of cross section to compensate for the crowded flux in the center leg and permit this leg 21 and the coil 5 to be made smaller with resultant saving in copper.

The deep or thick and narrow core attained by my invention also has the advantage that by reason of its depth or thickness, the portions of the core outside the coil may be made narrow and yet afford low reluctance, and the narrow outside portions not only reduce the length of magnetic path, but confine the magnetic flux to a narrow path of comparatively great depth or thickness. This insures quite a uniform distribution of the flux throughout the cross section of these narrow core portions and not only reduces the losses occasioned by irregular and un-

even distribution of the flux and the long flux paths of former constructions, but also aids greatly in reducing the instantaneous charging current.

5 The transformer core 19 is mounted in a supporting frame 25 having vertical corner angle irons 26 fastened together by tie bolts 27 and connected by cross bars 28 and supported on cross beams 29, supported by the 10 base. Due to the relative narrowness of the core sections and the elongation of the elliptical coil the over all dimensions of the transformer are sufficiently nearly equal in thickness and width so as to fit most advantageously in round tank 35, such a round tank being relatively strong and inexpensive in comparison with the oblong tanks hitherto usual.

The coil structure of this invention is 20 easily wound and permanently arched and self supporting throughout, giving the great mechanical strength required and permitting a unitary formation of the windings in compact and economical manner and at the same time providing a large number of continuous ventilating ducts carrying the cooling fluids to all portions of the coils evenly cooling all parts of the transformer coils and avoiding local highly heated portions 30 with rapid temperature gradients which would cause a relative stressing and wearing between the parts heated to different degrees. When assembled in the transformer it allows the core to be most efficiently designed and saves greatly in the amount of 35 material used and in the over all size of the transformer. Vertical ducts at the ends of the coil are exposed to unobstructed direct flow of the cooling oil and the coil wires 40 passing in continuous evolutions around through these end portions conduct thereto any heat tending to accumulate in the less accessible portions of the coil.

Aside from the advantages of my invention 45 as regards strength of construction, durability, economy in cost of manufacture, and the like, my invention greatly increases the efficiency of the transformer. This is due to the shape of the parts and their interrelation.

The shape of the coil is such that it gives a very uniform distribution of the magnetic flux created thereby, because there are no abrupt bends or sharp turns in the coil. 55 This avoids any tendency to overcrowd the magnetic flux at certain points. It consequently tends to create an evenly distributed flux of which all parts may be effectively and efficiently utilized.

60 Also the core is so shaped and related to the above form of coil that it receives and carries the magnetic flux created by the coil in a most effective and efficient manner. The contour of the core within the coil substantially conforms to and is in close proximity

to the inner surface of the coil and there are no wasted air spaces of any appreciable amount. The interior core by thus conforming to the contour of the interior of the coil preserves the uniform flux distribution as 70 set up by the coil and utilizes the space within the coil to a maximum degree. By reason of attaining a uniform distribution of flux in the interior core, the electromotive force induced in the secondary coils is likewise most efficiently set up because all parts of the secondary coils are quite uniformly 75 acted upon by the flux of the core. There is thus quite a uniformly distributed and harmonious action between the coils and core 80 and vice versa in all parts giving efficient and effective use thereof. Irregular and uneven interactions which tend to reduce efficiency are avoided.

A still further advantage of my invention 85 is that the instantaneous exciting current is very low, thus tending to prevent creation of surges in the transformer and also to protect the transformer from injury from surges on the line.

Also by my improvement, the coils have all parts quite fully surrounded by iron, within and without, which greatly aids in efficiency not only by the uniform relationship between coils and core, but also by the 95 low reluctance of the core as a whole and by the comparatively short length of paths in the magnetic circuit.

While in the particular embodiment shown the coil is illustrated in connection with the 100 unitary windings for a transformer having a double magnetic circuit, it is applicable to other forms and in particular the elliptical coil structure is equally adapted to sectional coils. The principle of the invention is not 105 confined to the specific structure described but is intended to cover such modifications thereof as fall within the scope of the appended claims.

I claim:

1. In a transformer, the combination of a laminated core having a core leg comprising parallel laminæ, the cross section of said parallel laminæ having the dimension perpendicular to the planes of said parallel laminæ greater than the width of the laminæ of said core leg, and a coil around said leg similarly having one dimension greater than the other and its greater dimension extending in the direction perpendicular to the 115 planes of said laminæ, the convolutions of said coil having continuous arch shaped curvature throughout.

2. In a transformer, the combination of a laminated core having a core leg comprising parallel laminæ, the cross section of said parallel laminæ having the dimension perpendicular to the planes of said parallel laminæ greater than the width of the laminæ of said core leg, and a coil around said leg of 120 125 130

- general elliptical form and having its major axis perpendicular to the planes of said laminæ, the convolutions of said coil having continuous arch shaped curvature throughout.
3. In a transformer, the combination of a laminated core having a core leg comprising parallel laminæ, the cross section of said parallel laminæ having the dimension perpendicular to the planes of said parallel laminæ greater than the width of the laminæ of said core leg, and a coil around said leg of general elliptical form and having its major axis perpendicular to the planes of said laminæ, the convolutions of said coil having continuous arch shaped curvature throughout, said coil comprising primary and secondary windings located one within the other.
4. In a transformer of the double magnetic circuit type, the combination of a core leg having its cross section of general elliptical form, and a surrounding coil having convolutions conforming generally to the shape of said core.
5. In a transformer, the combination of a laminated core having a double magnetic circuit and having the laminæ of its core located in parallel planes, the central leg of the core having its cross section of general elliptical form, and a coil around said leg having convolutions conforming generally to the form of said core leg and of arch shaped curvature throughout, the formation of said core leg being such as to provide angular ventilating spaces between the inside of the ends of said coil and adjacent parts of said core leg.
6. In a transformer, the combination of a laminated core having a core leg comprising vertical parallel laminæ, the cross section of said parallel laminæ having the dimension perpendicular to the planes of said parallel laminæ greater than the width of the laminæ of said core leg, a transformer coil of general elliptical form of continuous curvature throughout around said leg and having its major axis perpendicular to the planes of said laminæ and having successive windings one within the other, and a series of vertical ventilating strips spaced apart from each other and separating successive windings at all points and providing vertical ducts between said spaced windings.
7. In a transformer, the combination of a laminated core having a double magnetic circuit and having the laminæ of its core located in vertical parallel planes, the cross section of the parallel laminæ of the central leg of the core having the dimension perpendicular to the planes of said laminæ greater than the width of the laminæ of said leg, a coil around said leg and similarly having one dimension greater than the other and its greater dimension extending in the direction perpendicular to the planes of said laminæ, said coil comprising successive windings one within the other and each winding having continuous arch shaped curvature throughout, and a series of vertical ventilating strips spaced apart from each other and separating said successive windings at all points to form vertical ventilating ducts.
8. In a transformer, the combination of a laminated core having a double magnetic circuit and having the laminæ of its core located in parallel planes, a cross section of the parallel laminæ of the central leg of said core having the dimension perpendicular to the planes of said parallel laminæ greater than the width of the laminæ of said central core leg, and a coil of general elliptical form around said leg and having its major axis perpendicular to the planes of said laminæ, the convolutions of said coil having continuous arch shaped curvature throughout, and the width of the connecting parts of said core outside said coil being such that the magnetic flux carried by said connecting parts is distributed substantially uniformly therein.
9. In a transformer, the combination of a laminated core having a double magnetic circuit and having the laminæ of its core located in parallel planes, the central leg of the core having a cross section of said parallel laminæ with the dimension perpendicular to the planes of said parallel laminæ greater than the width of the laminæ of said core leg, and a coil around said core leg having gradually and continuously curved interior end portions, and the said central core leg conforming in general outline to and being in close proximity throughout to the inner surface of said coil.
10. In a transformer, the combination of a laminated core having a double magnetic circuit and having the laminæ of its core located in parallel planes, the central leg of the core having a cross section of said parallel laminæ with the dimension perpendicular to the planes of said parallel laminæ greater than the width of the laminæ of said core leg, and a coil around said core leg having gradually and continuously curved interior end portions, and the said central core leg conforming in general outline to and being in close proximity throughout to the inner surface of said coil, and the connecting portions of said core outside said central core leg also having a cross section with the dimension perpendicular to the planes of its parallel laminæ greater than the width of its laminæ and having such width that the magnetic flux is distributed substantially uniformly through the cross section of said connecting outside portions of the core.
11. In a transformer, the combination of

a laminated core having a core leg comprising parallel laminae, the cross section of said parallel laminae having the dimension perpendicular to the planes of said parallel laminae greater than the width of the laminae of said core leg, and a coil around said leg similarly having one dimension greater than the other and its greater dimension extending in the direction perpendicular to the

planes of said laminae, the convolutions of said coil having a continuously and gradually changing curved inner surface throughout all parts of its convolutions, and the said core leg conforming in general outline and being in close proximity throughout to 15 the inner surface of said coil.

ROBERT V. BINGAY.
